UNITED STATES PATENT OFFICE

171,802

TRANSFORMER

Roger B. Kerr, Jamestown, R. I., assignor to General Electric Company, a corporation of New York

Application August 10, 1953, Serial No. 26,361

Term of patent 14 years

(Cl. D26—15)

To all whom it may concern:

Be it known that I, Roger B. Kerr, a citizen of the United States, residing at Jamestown, in the county of Newport, State of Rhode Island, have invented a new, original, and ornamental Design for a Transformer, of which the following is a specification, reference being had to the accompanying drawing, forming a part thereof, in which.

Fig. 1 is a front perspective view of a transformer, showing my new design, and

Fig. 2 is a slightly reduced rear elevation of the same.

The side mat shown in the drawings is the same as its corresponding side shown in Figure 1.

I claim:

The ornamental design for a transformer, as shown and described.

ROGER B. KERR.
